UNITED STATES PATENT OFFICE.

EMANUEL RAUS, OF PRAGUE, AUSTRIA-HUNGARY.

SAFETY-BALL FOR TRAM PROTECTING-ROLLERS.

SPECIFICATION forming part of Letters Patent No. 707,255, dated August 19, 1902.

Application filed April 30, 1902. Serial No. 105,319. (No model.)

To all whom it may concern:

Be it known that I, EMANUEL RAUS, a subject of the Emperor of Austria-Hungary, residing at Prague, in the Kingdom of Bohemia, 5 Austria-Hungary, have invented a new and useful Safety-Ball for Tram Protecting-Rollers, of which the following is a specification.

My invention relates to improvements in protecting-rollers for tramway-cars, which 10 rollers are covered with elastic balls or fingers; and the objects of my invention are, first, to make the shock of the protecting implement against the person or animal which it meets as soft and gentle as possible; second, to assure the grasping effect of the upward rolling and sideward action of the rollers, and, third, to facilitate the replacement of damaged pieces of the elastic covering. I 15 attain these objects by the mechanism illustrated in the accompanying drawings, in which—

Figures 1 and 2 represent the protecting-rollers respectively in vertical and horizontal projection. Figs. 3 and 4 represent a roller 20 in cross-section and in horizontal projection. Figs. 5 and 6 represent the elastic ball or finger in cross-section and in horizontal projection.

Similar numerals refer to similar parts 25 throughout the several views.

1 and 2 are the well-known protecting-rollers, which are rotated opposite to the direction of rotation of the wheels by the usual means if the car is running. Their axes are horizontal and inclined to each other, so as to form a kind of wedge, of which the point is in the middle and in front of the car for the purpose of making it impossible for an object met on the way to be drawn under the wheels of the 30 car. Any person or animal which may be caught by the car running against it is supposed to be carried upward from the street pavement and sideward from the car. It has been proved that this well-known arrangement does not satisfy the expectations placed 35 upon its saving virtues. Even if the rollers are covered with soft material or with a cover of india-rubber they do not grasp sufficiently, and the shock remains very violent for any 40 person collided with. For the purpose of obviating the said drawbacks of this arrangement and making it really useful and effect-

ive I provide the rollers on their surface with grooves 10, which are parallel to their axes and have undercut or dovetailed sides 5. Fingers or balls 3, of india-rubber or a similar elastic material, which have rectangular soles 6, with beveled longitudinal edges 4 fitting into said grooves 10, are slid into these grooves, so as to touch each other. They hold in the 45 grooves, because of the dovetails, but are secured besides this with iron or similar bands 9, slung around the rollers on the ring parts which lie between the annular rows of fingers or balls, such bands being properly fastened 50 with clamping-screws or in other appropriate ways upon the rollers. These bands may but need not be covered with fixed iron bars 7, which in this case are fastened to the car-frame and protect the rollers and at the same 55 time afford a fender-grating or a part of one. The balls or fingers are on their top either smooth, or they may be provided with elevations 8, and the like, for the sake of grasping more effectively. Such balls or fingers if arranged in the indicated way can easily be replaced in case of damage, one by one, and are therefore economical.

I am aware that prior to my present invention protecting-rollers have been known and 60 used which were covered with different elastic and properly soft materials and fabrics. I therefore do not claim such rollers nor such covers in general.

What I claim, and desire to secure by Letters Patent of the United States, is—

1. The combination with tramway protecting-rollers having undercut or dovetailed longitudinal grooves, of elastic balls or fingers 3 having rectangular soles with beveled longitudinal edges engaging the longitudinal grooves in the periphery of said rollers, substantially and for the purpose as set forth.

2. The combination with tramway protecting-rollers, having undercut or dovetailed longitudinal grooves, of elastic balls or fingers having rectangular soles, with beveled longitudinal edges, engaging said longitudinal grooves, and bands 9 encircling the rollers and clamping over the projecting ends of said 95 soles in the annular spaces between the balls.

3. The combination with tramway protecting-rollers having undercut or dovetailed longitudinal grooves, of elastic balls or fingers

having rectangular soles, with beveled longitudinal edges, engaging said longitudinal grooves, bands 9 encircling the rollers in the annular spaces between the balls and above 5 the projecting ends of said soles and bars 10 attached to the car-frame and embracing said bands.

In witness whereof I have hereunto set my hand in presence of two witnesses.

EMANUEL RAUS.
